US0D1056950S

(12) **United States Design Patent** (10) **Patent No.:** **US D1,056,950 S**
(45) **Date of Patent:** **** Jan. 7, 2025**

(54) **ELECTRONIC DEVICE WITH GRAPHICAL
USER INTERFACE**

(71) Applicant: **Apple Inc.**, Cupertino, CA (US)

(72) Inventors: **Alan C. Dye**, San Francisco, CA (US);
Wan Si Wan, Sunnyvale, CA (US)

(73) Assignee: **Apple Inc.**, Cupertino, CA (US)

(**) Term: **15 Years**

(21) Appl. No.: **29/853,757**

(22) Filed: **Sep. 19, 2022**

(57) **CLAIM**

The ornamental design for an electronic device with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is another embodiment of; and, FIG. 3 is a front view of an electronic device having a display screen with the graphical user interface of FIG. 1 applied to the display screen. The graphical user interface design of FIG. 2 may be similarly applied thereto.

The broken lines in the figures show a display screen or portion thereof, or an electronic device having a display screen, and form no part of the claimed design.

**1 Claim, 3 Drawing Sheets
(2 of 3 Drawing Sheet(s) Filed in Color)**
